UNITED STATES PATENT OFFICE.

JAMES W. EASTON, OF NEW YORK, N. Y.

DYNAMO-ELECTRIC MACHINE.

SPECIFICATION forming part of Letters Patent No. 363,128, dated May 17, 1887.

Application filed July 3, 1886. Serial No. 207,041. (No model.)

To all whom it may concern:

Be it known that I, JAMES W. EASTON, a subject of the Queen of Great Britain, residing in New York, in the county and State of New 5 York, have invented certain new and useful Improvements in Dynamo-Electric Generators, of which the following is a specification.

My invention relates to the construction and method of organizing dynamo-electric generators.

The object of the invention is to so organize two or more dynamo-electric generators and their circuits that currents of different character may be derived therefrom, while the machine will be to a certain extent automatically regulating.

In carrying out the invention the neutral plate of one generator preferably serves as the neutral plate of the second. The field-magnet 20 coils of two or more of the generators are connected in circuit with one of the armatures, and supplementary coils are employed upon the field-magnets of one or more of the generators as regulating-coils by including them in 25 the circuit of another armature.

In the accompanying drawings, Figure 1 is a side elevation, partly in diagram, illustrating the construction of the machine and organization of the circuits; and Fig. 2 illustrates a 30 modification.

Referring to the figures, A represents a shaft, upon which there are carried, in this instance, two armatures, A' and a'. The armature A' revolves in a field established by two pole-pieces, B' and B², derived from the field-magnets C' and C², respectively. The field-magnets are connected by neutral plates D' and D² in the usual manner. The armature is provided with a suitable commutator or collector, E, 35 having brushes F' and F². Conductors 1 and 2 lead from these brushes respectively through the coils G' G' and G² G² of the field-magnets; and in the circuit there is included a work-circuit, L, which, in this instance, is represented 40 as being employed for operating arc lights M M. From the neutral plate D² there are derived field-magnets c' c², having pole-pieces b' and b² applied to the armature a'. A portion, g' g', of the coils of these field-magnets are included in the circuit of the armature A' in series with the coils G' G' and G² G². In this 45 manner the neutral plate D² serves as a neutral 50

plate for both sets of field-magnets, and the main magnetizing effect for the field-magnets b' and b² is occasioned by the currents from 55 the armature A'.

The armature a' and its field-magnets are represented in this instance as being smaller than the armature A' and its field-magnets; but the two may be of the same size. The armature A' is represented as supplying currents for the arc lights, and the currents required for this purpose are therefore constant in quantity. The armature a' supplies currents for incandescent lighting, the lights m m being included 60 in multiple arc between conductors l' l², leading from the respective brushes f' and f², applied to the commutator or collector e of the armature a'. The currents required for incandescent lighting are of constant electro-motive force, or, in other words, the difference of potential between conductors l' and l² is required to be constant. For this purpose the field of force applied to the armature a' should be to some extent automatically regulating. 65 This is accomplished by including a section, g' g², of the coils surrounding the field-magnets b' and b² in the circuit of the armature a', as shown. In this manner variations in the current flowing through the translating-circuit l' l² will occasion variations in the strength of 70 the field applied to the armature a' and compensate for the increasing and decreasing of 75 the current in the armature-coils.

If desired, the arrangement of circuits may 80 be reversed, the magnetizing-coils of the field-magnets of the larger armature being included in the circuit of the smaller armature, and a portion sufficient to regulate the current from 85 the larger armature included in its circuit in 90 series.

In Fig. 2 a method of winding is illustrated, in which the currents from the armature a' are employed to excite the field-magnets of the armature A', while the coils g' g² of the smaller 95 field-magnets are included in the working-circuit of the armature A'. In this manner the currents from the armature A' will counteract their own disturbing effect by increasing or decreasing the field of the exciting-armature a', which in turn will vary the current through 100 the coils G' G' and G² G². By this construction a less amount of wire is required in the circuit of the armature A' to accomplish the

same end as results from including the coils G' and G'' in the circuit of the armature A' .

In the construction shown in Fig. 2 the arc lights are included in the circuit of the armature a' , which is a constant-current circuit, and the incandescent lights are supplied by the constant potential currents from the armature A' .

I claim as my invention—

1. The combination, with two field-magnets and their respective armatures, the one organized to deliver currents constant in quantity, and the other to deliver currents of a constant electro-motive force and variable quantity, of a circuit derived from the armature delivering currents of constant quantity including a portion of the field-magnet coils of the other armature, and a circuit derived from the last-named armature including the remaining coils of its field-magnet.
2. The combination, substantially as hereinbefore set forth, of two armatures, one delivering currents constant in quantity and of variable electro-motive force, and the other delivering currents of constant electro-motive force,

their respective field-magnets, magnetizing-coils applied to both of said field-magnets, a circuit derived from the first-named armature including all of its own field-magnet coils and a portion of the field-magnet coils of the other armature, and a circuit derived from the second armature, including the remainder of its own field-magnet coils.

3. The combination of two armatures, their respective field-magnets, a circuit derived from one of said armatures, including a portion of the field-magnet coils of the other armature, and a circuit derived from the second armature including the remaining portion of said field-magnet coils and all the field-magnet coils of the first-named armature.

In testimony whereof I have hereunto subscribed my name this 25th day of May, A. D. 1886.

JAMES W. EASTON.
